UNITED STATES PATENT OFFICE.

ANDREW CAMPBELL, OF BROOKLYN, ASSIGNOR TO JOHN McLOUGHLIN AND EDMUND McLOUGHLIN, OF NEW YORK, N. Y.

VARIABLE BED-MOTION FOR PRINTING-MACHINES.

SPECIFICATION forming part of Letters Patent No. 278,875, dated June 5, 1883.

Application filed August 24, 1882. (No model.)

To all whom it may concern:

Be it known that I, ANDREW CAMPBELL, a citizen of the United States, residing at Brooklyn, Kings county, New York, have invented 5 an Improved Variable Bed-Motion for Printing-Machines, of which the following is a specification.

My invention relates to that class of presses in which the bed bearing the form reciprocates 10 under the printing-cylinder; and the invention consists, in part, in a novel mechanism for imparting to the bed its reciprocating movement, whereby it is moved forward under the impression at the same speed as the periphery of 15 the cylinder and backward at a greater speed.

It also relates to the bearers which re-enforce the bed under the strain of the impression. When the impression is off the bed, and it is 20 moving back, it is desirable that it shall move rapidly, and this I accomplish by the novel mechanism which I will now describe with reference to the accompanying drawings.

Figure 1 is a vertical longitudinal section of part of a printing-press arranged to illustrate my present improvements, the sectional parts being cut along the line 1 1 in Fig. 2. Fig. 2 is a transverse section, viewed from the right, and cut in the plane of the line 2 2 in Fig. 1, the gear M being shown displaced, as 25 hereinafter explained. Fig. 3 is a similar section cut in the plane of the line 3 3 in Fig. 1. Fig. 4 is an under side view of the bed-rack and the driving-pinion. Fig. 5 is a plan or top view of the compound driving-pinion. 30 Fig. 6 is a fragmentary sectional view cut on line 6 6 in Fig. 7 and looking in the same direction as Fig. 1; and Fig. 7 is a horizontal section of Fig. 6, cut in the plane of line 7 7 therein. Figs. 4 and 5 are drawn to a larger 35 scale than the remaining figures.

In the drawings I have only shown a part of a printing-press, it not being deemed necessary to a full understanding of my invention that any but the parts adjacent to and operating in 40 connection with my improvements should be shown.

Let A represent the ordinary frame of a printing-press, and B the bed, arranged to reciprocate on bearers or slides on the same.

50 C is a compound rack, which is formed on or rigidly secured to the bed. This rack has a pe-

ciular construction, and must be described with reference to the compound pinion D, which drives it. The compound rack is endless or continuous, as shown in Fig. 4, the teeth forming the parallel sides being connected at the ends by semicircular rows of teeth a a. The line x x in Fig. 4 shows the true axis of the rack, and it will be seen that the row of teeth b on one side is nearer the axis than the row c on the opposite side; and it will also be seen (Figs. 1 and 2) that the row b is in a lower plane than c, while the semicircular rows a a are in a plane between the other two. The pitch of these three rows or racks is the same, and the teeth at the extremities of the rows or racks coincide in a vertical plane—that is to say, the last tooth—or space, as the case may be—in row b coincides with the first tooth in row a, and may be a vertical prolongation thereof, 70 while at the other end of row a its last tooth coincides with and may form a vertical prolongation of the first tooth of row c. Thus the rack is made continuous; but its ends and sides are in three different horizontal planes. 75

The compound pinion D is composed of three separate pinions, a', b', and c', which I will call, for convenience, "sections." These sections are arranged in planes to correspond and coincide with the planes of the rows of teeth in rack C—that is to say, the rows a a are in the same plane with section a', row b with section b', and row c with section c'. Sections b' and c' are concentric—that is, their axes coincide with each other and with the vertical shaft E, upon which they are mounted. Section a' is eccentric with the others, a tooth, y, on one side of it coinciding with a tooth on section b', and a tooth, z, on its opposite side coinciding with a tooth on section c'. These sections may be all cast in one piece, if desired, in which case each of the teeth y and z on a' would form, with its respective coincident tooth on b' or c', one tooth with a long face.

Mounted on the upper end of shaft E, above 95 the pinion, is a guide wheel or roller, F, which moves in a channel, d, around the rack C, and serves to keep the teeth of the pinion engaged with those of the rack.

The shaft E revolves with pinion D continuously in one direction; and in order that the pinion may be kept in its proper position with

respect to the rack, to reciprocate the bed, the said shaft is mounted vertically in a frame, G, which is arranged to move transversely and across the line of travel of the bed. The upper part of frame G is provided with a rod or bar, H, Fig. 2, which slides in fixed guides or bearings *e e*, and on the lower part of shaft E is a bevel-pinion, I, which meshes with a spur bevel-wheel, J. This last wheel is keyed to a shaft, K, which has a collared bearing in the frame G, and is arranged to play longitudinally in another fixed bearing, *f*, in the frame A.

Motion is imparted to shaft K by means of a toothed wheel, L, on said shaft, which is arranged to mesh with a long-faced toothed wheel, M, on a shaft, N, which shaft may be the main power-shaft of the machine. In Figs. 1 and 3 I have shown the wheel M in its proper position when driven from the printing-cylinder, but in Fig. 2 I have shown it in another and lower position in order not to obscure other parts. It may be placed in any position around the wheel L consistent with the general arrangement of the machine.

To further strengthen the frame G and relieve the slide-bar H of undue strain, I provide a fixed cross-bar, P, arranged parallel with the slide-bar H and close against the frame G, which is connected to it by a dovetail slide, as shown in Fig. 1. The bar P thus receives the thrust due to the propulsion of the bed. Instead of the dovetail, two bars, P, may be used, the frame G working between them. The lower portion of the frame G slides in a foot, Q, which projects from and is fixed to or cast as a part of a cross-frame, A', which connects the two side frames of the press.

I will now describe the operation of the mechanism for propelling the bed.

We will suppose the bed to be advancing with the impression on. The pinion-section *c'* (shown as containing twelve teeth) is in mesh with teeth *e* of rack C, and the bed is moving at its minimum speed. As the bed nears the end of its forward movement the eccentric section *a'* (shown as containing fourteen teeth) engages the semicircular row of teeth *a* at the end of the rack. As the rack is fixed to the bed and cannot move laterally, the pinion D rolls around the end of the rack to the opposite side, when the teeth of section *b'* engage the teeth in row *b* of the rack. To enable the pinion to thus shift its position transversely across the bed, the frame G (see Fig. 2) moves along with the bar H, shaft K, and wheel L transversely the proper distance, the bar H sliding in the bearings *e* and shaft K in the bearings *f*. The wheel M is wide enough to permit of the movement of wheel L without throwing it out of mesh. The larger section *b'* of the pinion D (shown as containing sixteen teeth) being now in mesh with row *b* of the rack-teeth, the bed is moved back at the maximum speed. With the proportions herein shown, but which may, of course, be departed from, the ratio of the forward to the

backward movement of the bed will be as three to four.

In constructing the rack C and pinion D care must be taken to proportion the number of teeth in the rack to those in the pinion, so that the eccentric section *a'* will properly engage with the semicircular rows *a* of the rack at both ends. It will also be observed that as a tooth on the pinion corresponds with a space on the rack it will be necessary to choose whether the opposite teeth (*y* and *z* in Fig. 5) of the eccentric section *a'* of the pinion shall be made to coincide with teeth on the other sections, or whether spaces shall be thus made to coincide. If the teeth on the pinion are made to coincide, then the terminal spaces on the rack must be made to coincide. This is the construction adopted in the drawings.

It will be seen that the pinion-sections *b'* and *c'* are the ones that are relied upon to propel the bed, the function of the eccentric section *a'* being confined to shifting the pinion-shaft laterally at the end of the stroke and to insuring the correct intermeshing of the sections *b'* and *c'* with the corresponding sections of the rack. Hence the section *a'* is not wholly essential, as it might be dispensed with if other suitable means were provided for shifting one of the propelling-sections out of and the other into engagement with the rack at each end of the stroke.

In lieu of placing the rack as shown, with the pinion-shaft vertical, the rack might be set on edge and the pinion-shaft be arranged to lie in a horizontal plane. In this case the pinion would shift in a vertical plane. The wheels L and M might be transposed, the long-faced pinion being then on shaft K. The axis of the shaft E might remain stationary and the rack C be mounted on the bed B, so as to slide laterally thereon at each end of the stroke.

The bed B is mounted in somewhat the usual manner upon two longitudinal sliding bearings, S S, arranged near each side of the press. In my construction there are two longitudinal girders, R R, resting on the transverse frames of the machine, and each having a groove, *g*, in its top side, in which groove roll a series of anti-friction rollers, *i i*, and on these rollers a runner, *h*, on the under side of the bed travels. A sliding frame, T, fits in between the walls of the groove *g* and embraces the sides of the runner *h*, thereby guiding the bed laterally, and the rollers *i i* fit between transverse bars *l l* of this frame, whereby they are kept in proper relative position. The two frames T T are propelled at the same speed as the rollers *i i* by a pinion, *n*, pivoted to each, and engaging a stationary rack, *m*, below and a rack, *m'*, fixed to the bed above. The weight of the bed is borne entirely by these bearings, except directly beneath the cylinder B', where it receives the strain of the impression, it being there re-enforced by a central bearing wheel or roller, O, which is arranged at such height that the under surface of the center portion of the rack C rolls over it and bears upon it,

whereby the middle of the bed is upheld and prevented from sagging under the pressure of the impression. This under bearing-surface of the rack extends beneath the entire length 5 of the form, and, being of considerable depth and strength, serves to transmit the support afforded by the wheel O to the bed for some distance in front of and behind the wheel, thereby affording an extended support to the 10 bed. Prior to my invention the center bearing-roller has been in direct contact with the under side of the bed, no rack or other deep and strong re-enforce being interposed, and it has been mounted on a shaft having bearings 15 in the external side frames of the machine, and adjustable by screws arranged to elevate the bearing-blocks. It is important in doing fine printing that the bearing-roller shall uphold the bed with the utmost rigidity, as a very 20 slight yielding or springing under the heavy strain required will materially impair the impression. To this end I mount my wheel O on a short shaft and provide it with bearings arranged close to it on each side, both bearings 25 forming part of one frame, U, which extends beneath the wheel, and is mounted on the rigid transverse frame A' of the press. Thus the pressure is transmitted directly downward through the wheel O and frame U to the frame 30 A', whereby the center of the bed is rigidly re-enforced and upheld, and all sagging or springing sufficient to affect the impression is prevented. The wheel O is adjustable vertically to properly regulate the impression in the 35 center of the bed by raising or lowering its frame U bodily.

Beneath the frame U, and between it and the frame A', is a wedge, q, of a width preferably equal to the length of the base of the 40 frame U, and the frame is fastened down by screws or bolts p p engaging the frame A'. To adjust the frame, the screws p p are loosened, and the wedge q is advanced or retracted by turning screws r r, or in any other suitable 45 manner engaging lugs s s, whereupon the screws p p are again tightened, making all firm. By this means the pressure borne by the wheel O is not sustained by the adjusting-screws, but is transmitted through the solid material of 50 the wedge.

Having thus fully described my invention, I claim—

1. The combination, with the reciprocating bed of a printing-press, of an endless rack connected thereto, and a compound pinion composed of sections of different diameters meshing with said rack, one section arranged to mesh therewith while driving the bed in one direction, and another to mesh therewith while 55 driving the bed in the opposite direction, whereby the bed is driven at a greater speed in one direction than in the other, substantially as set forth.

2. The reciprocating bed of a printing-press 60 provided with a compound rack, C, in combination with a compound driving-pinion, D, consisting of sections of teeth of different di-

meters mounted to travel across the face of the rack, and adapted to drive the bed faster in one direction than in the other, substantially 70 as set forth.

3. The combination, with the bed of a printing-press, of an endless rack connected thereto, and consisting of sections of teeth arranged in different planes, and a compound pinion having sections of teeth arranged in different planes corresponding to the teeth of said rack, and its sections formed of different diameters, whereby the bed shall be driven faster in one direction than in the other, substantially as 80 set forth.

4. The combination, in a printing-press, as a means for giving to the bed a variable reciprocating movement, of the compound rack C, provided with rows of teeth a, b, and c, and 85 the channel d, of the compound pinion D, comprising the sections a', b', and c', the guide-wheel F, shaft E, the frame G, arranged to move in guides across the line of travel of the bed, and suitable mechanism, substantially as 90 described, for rotating the pinion D, all arranged to operate substantially as set forth.

5. The combination of the bed, the compound rack and pinion, the pinion-shaft, the guided frame G, bevel-gears I and J, shaft K, 95 toothed wheel L, and the long-faced toothed wheel M, meshing therewith, all arranged substantially as set forth.

6. The combination of the reciprocating bed B, the bed-rack affixed longitudinally to its 100 under side along the middle thereof and beneath the form, and the bearing wheel or roller O, arranged with its axis directly beneath the axis of the cylinder and to bear upon said rack, and thereby sustain the bed under the strain 105 of the impression, substantially as set forth.

7. The combination, with the bed of a press, of sliding guides or supports arranged beneath it, one on each side of its middle, and a bearing-wheel arranged beneath its middle and directly beneath the axis of the printing-cylinder, with a bearing-frame for said wheel 110 mounted on a rigid portion of the frame of the press, beneath said wheel and vertically adjustable thereon, substantially as set forth.

8. The combination, with the bed B and cross-frame A' of a printing-press, of a bearing-wheel, O, arranged beneath the middle of the bed, with a bearing-frame, U, for said wheel extending beneath the same, a wedge, 120 q, resting on said frame A' directly beneath the wheel O, and bearing the frame U, and fastening-screws p p, whereby the wheel O is rendered vertically adjustable and its downward pressure is transmitted directly downward through its frame and the wedge to the frame A', substantially as set forth.

In witness whereof I have hereunto signed my name in the presence of two subscribing witnesses.

ANDREW CAMPBELL.
